UNITED STATES PATENT OFFICE

2,512,467

SINGLE ELEMENT, UNIDIRECTIONAL,
DYNAMIC MICROPHONEHarry F. Olson, Princeton, and John Preston,
Hopewell, N. J., assignors to Radio Corporation
of America, a corporation of Delaware

Application July 31, 1946, Serial No. 687,419

4 Claims. (Cl. 179—115.5)

1

This invention relates to sound translating apparatus, and more particularly to a single element, dynamic microphone of the type disclosed in the Olson patent, No. 2,301,638.

In the aforementioned patent, there is disclosed a dynamic microphone employing a single ribbon conductor arranged for vibration in the air gap of a magnetic system in response to sound waves impinging thereon. The ribbon is terminated at its rear face by a long tube or pipe filled with suitable acoustic resistance material. Immediately behind the ribbon, the aforementioned pipe is provided with an opening which may be closed off more or less to provide either a non-directional characteristic when this opening is entirely closed, a bi-directional characteristic when this opening is entirely open, or a unidirectional characteristic when this opening is only partially closed off. Where it is desired that the microphone shall have only a unidirectional characteristic, an opening of fixed, suitable size is provided in the pipe and no provision need then be made for varying the size of the opening.

As constructed heretofore, unidirectional microphones of this type have suffered from the disadvantage that the response is not uniform throughout the entire frequency range over which the microphone is responsive. This is due largely to the acoustic resistance provided by the pipe behind the ribbon.

The primary object of our present invention is to provide an improved, single element, dynamic microphone which will be free from this disadvantage.

More particularly, it is an object of our present invention to provide an improved microphone of the type set forth which will have a more uniform response, particularly in the low frequency region, than similar microphones of the prior art.

Another object of our present invention is to provide an improved form of single element, dynamic microphone as aforesaid into which similar microphones of the prior art can be converted readily.

It is also an object of our present invention to provide an improved microphone as aforesaid which is simple in construction and highly efficient in use.

In accordance with our present invention, we place over the opening in the pipe behind the vibratory ribbon or other similar conductor a screen covering, preferably of fine mesh, which provides an acoustic resistance for this pipe opening. The acoustic resistance of this screen, which is comparable to the acoustic reactance of the pipe opening, serves to compensate for the acoustic resistance in the ribbon branch of the microphone and thus provides an improved directional characteristic as will be described more fully herein-after.

2

The novel features of our invention, as well as additional objects and advantages thereof, will be understood better from the following description of two embodiments thereof, when read in connection with the accompanying drawings in which

Figure 1 is a front elevation of a portion of a microphone constructed in accordance with one form of our present invention,
10. Figure 2 is a perspective view of the structure shown in Figure 1, as seen from the rear of the microphone,

Figure 3 is a sectional view thereof taken on the line 3—3 of Fig. 1,

15. Figure 4 is an electrical wiring diagram of a circuit in which the microphone of our present invention may be employed.

Figure 5 is the electrical analogue of the acoustical circuit involved in the microphone illustrated by Figs. 1, 2 and 3,

20. Figure 6 is a graph showing the directional characteristic of an ideal unidirectional microphone,

Figure 7 is a graph showing the response of our improved microphone both from the front, or at 0°, and from the rear, or at 180°, the latter both with and without the fine mesh screen applied to the microphone,

25. Figure 8 is a perspective view of a microphone constructed in accordance with another form of our present invention, and

Figure 9 is the electrical analogue of the acoustical circuit involved in the microphone illustrated by Fig. 8.

30. Referring more particularly to the drawings, in which similar reference characters designate corresponding parts throughout, there is shown a pair of pole pieces 1 connected to a pair of magnets 3 which are supported by a bar 5 of magnetic material, the pole pieces 1 being spaced from each other to provide an air gap 7 through which extends a magnetic field supplied by the magnets 3 in known manner. Vibratively mounted in the air gap 7 is an elongated, conductive ribbon 9 of well known form. The longitudinal or side edges of the ribbon 9 are spaced somewhat from the adjacent edges of the pole pieces 1 to provide slits 7a which afford adequate clearance to permit the ribbon 9 to vibrate freely in response to acoustical waves impinging thereon.

35. Behind the ribbon 9, there is mounted a closed pipe 11 which may terminate in a suitable labyrinth structure or the like 13 (Fig. 3) filled with tufts of felt or similar damping material 15, the pipe 11 and labyrinth structure 13 with its damping material 15 acting as an acoustic resistance which terminates the ribbon 9. The ribbon 9 substantially closes the mouth of the pipe 11 at its upper end, as clearly shown in Figure 3 and in a 40 manner more fully disclosed, for example, in Re-

issue Patent No. 19,115 granted to H. F. Olson and J. Weinberger. The pipe 11 is provided behind the ribbon 9 with an opening 17 of such size as to impart to the microphone a substantially unidirectional characteristic in the manner more fully disclosed in the above mentioned Olson Patent No. 2,301,638.

In accordance with our present invention, we place over the opening 17 a screen 19 having a mesh preferably of about 120 threads per inch, with a thread diameter of 0.006 inch. It is the provision of this screen 19, which may be made of wire or any other suitable material, which imparts to the microphone an improved response.

The ribbon or conductor 9 may be connected through a first transformer 21, a transmission line 23 and a second transformer 25 to an amplifier 27, as shown in Fig. 4, for amplifying the voltages generated by the ribbon 9 upon vibration thereof through the magnetic field in the air gap 7. From a consideration of the acoustical system represented by Figure 5, it will be seen, by means of the following analysis, how the addition of the screen 19 improves the response of the microphone:

In the acoustical circuit of Figure 5, there are shown three branches Z_{A1} , Z_{A2} and Z_{A3} . In the branch Z_{A1} ,

M_s =inertance of the slits 7a,

r_{as} =acoustical resistance of the slits 7a,

M_R =inertance of the ribbon 9,

r_{AR} =acoustical resistance of the ribbon 9,

C_{AR} =acoustical capacitance of the ribbon 9,

M_A =inertance of the air load upon the ribbon 9,

r_{AA} =acoustical resistance of the air load upon the ribbon 9;

Z_{AE} =acoustical impedance due to the electrical circuit shown in Fig. 4. The value of Z_{AE} is given by the equation

$$Z_{AE} = \frac{(\beta l)^2}{A^2 (Z_{E1} + r_{ER}) 10^9} \quad (1)$$

where

β =flux density in the air gap 7,

l =length of the ribbon 9;

A =area of the ribbon;

Z_{E1} =electrical impedance of external load on ribbon 9, as shown in Fig. 4, and

r_{ER} =electrical resistance of the ribbon 9 (see Fig. 4).

Z_{A1} is the acoustical impedance of the branch composed of the above elements.

In the branch Z_{A2} ,

M_2 =inertance of the air in aperture or opening 17

M_3 =inertance of the screen 19

r_{A3} =acoustical resistance of the screen 19

M_4 =inertance of the air load upon the screen 19 and the aperture 17

r_{A4} =acoustical resistance of the air load upon the screen 19 and the aperture 17.

Z_{A2} is the acoustical impedance of the branch composed of the above elements.

In the branch Z_{A3} ,

$Z_{A3}=r_{AP}$ =acoustical resistance of the acoustically damped pipe 11, 13, 15.

The sound pressure acting on the open or front side of the ribbon 9 may be written

$$p_1 = p_{\phi_1} e^{j(\omega t + \phi_1)} \quad (2)$$

where

p_{ϕ_1} =amplitude of the sound pressure of the sound wave upon the ribbon 9,

$$\omega = 2\pi f$$

f =frequency of the sound,

t =time reckoned from any arbitrary zero point of time, and

ϕ_1 =phase angle of the sound pressure upon the ribbon with respect to an arbitrary reference point.

The sound pressure acting on the aperture or opening 17 at the screen 19 may be written

$$p_2 = p_{\phi_2} e^{j(\omega t + \phi_2)} \quad (3)$$

where

p_{ϕ_2} =amplitude of the sound pressure upon rear surface of the aperture, and

ϕ_2 =phase angle of the sound pressure upon the rear surface of the aperture with respect to the same, arbitrary reference point as used in Equation 2.

15 The reference point for the phase may be changed so that

$$p_1 = p_{\phi_1} e^{j(\omega t)} \quad (4)$$

and

$$p_2 = p_{\phi_2} e^{j(\omega t + \phi_3)} \quad (5)$$

where

$$\phi_3 = \phi_1 - \phi_2$$

30 The phase angle ϕ_3 is a function of the angle of the incident sound

$$\phi_3 = \phi \cos \theta \quad (6)$$

where

θ =angle between the normal to the surface of the ribbon and the direction of the incident sound, and

ϕ =constant phase angle obtained from the geometry of the microphone.

Specifically the phase angle ϕ , in degrees, is the effective path length, in centimeters, from the ribbon 9 to the aperture or opening 17 on the back of the pipe 11 multiplied by 360 and divided by the wavelength of the sound, in centimeters.

45 The volume current of the ribbon due to the sound pressure p_1 is

$$\dot{X}_1 = \frac{p_1 (Z_{A2} + Z_{A3})}{Z_{A1} Z_{A2} + Z_{A1} Z_{A3} + Z_{A2} Z_{A3}} \quad (7)$$

50 The volume current of the ribbon due to the sound pressure p_2 is

$$\dot{X}_2 = \frac{p_2 (Z_{A3})}{Z_{A1} Z_{A2} + Z_{A1} Z_{A3} + Z_{A2} Z_{A3}} \quad (8)$$

55 The resultant volume current $\dot{X}_R$ of the ribbon 9 is the difference between the volume currents defined by equations 7 and 8, or

$$\dot{X}_R = \dot{X}_1 - \dot{X}_2 \quad (9)$$

60 The voltage output of the ribbon is:

$$e = \beta l \frac{\dot{X}_R}{A} \quad (10)$$

From Equations 9 and 10, it will be seen that, with the above system, it is theoretically possible, by proper choice of constants, to obtain the cardioid characteristic of Fig. 6. At 180°, the theoretical response is zero. An experimentally determined response characteristic is shown in Fig. 7. It will be seen that the response characteristic at 180° (curve A) is not zero. It is down about 40 db in the mid-range. This approximates the ideal condition because 40 db represents an energy ratio of 10,000 to 1. However,

75 in the low frequency range (40 to 200 cycles), the

cancellation is not as good. We have found that the addition of the fine mesh screen 19, which provides the additional acoustical elements M_3 and r_{A3} , increases the cancellation at 180° in the low frequency region to provide the characteristic shown by the curve B in Fig. 7. This is due to the fact that the addition of the screen 19 introduces an acoustic resistance which compensates for the acoustic resistance in the ribbon branch and thereby produces better cancellation.

From the foregoing description, it will undoubtedly be apparent to those skilled in the art that we have provided an improved, single element, dynamic microphone which has a more desirable response than similar microphones of the prior art. It will also be apparent that various changes and modifications may be made within the spirit of our present invention. For example, in place of a single screen 19, a slide 35, or other suitable support, having several discrete screens 37, 39, 41, may be adjustably mounted on the pipe 11 over the opening 17. In Fig. 8 of the drawings, the slide 35 is shown comprising a framework provided with openings 43, 45, 47 over which the screens 37, 39, 41 are mounted, each of the screens being of different mesh to provide a plurality of acoustic resistances of different values for the opening 17. The slide 35 is slidably mounted on the pipe 11 by brackets 49, 51 attached to the pipe 11 on either side of the opening 17 and arranged in a manner such that any one of the openings 43, 45, 47 may be brought into registration with the opening 17 to thereby place screens of different mesh over the opening 17 and thus vary the degree of cancellation from the back of the microphone at will.

Figure 9 is an electrical analogue of the modification of our invention illustrated in Figure 8. As in the case of the analogue illustrated in Figure 5, there are also shown in Figure 9 three branches Z_{A1} , Z'_{A2} and Z_{A3} . The branches Z_{A1} and Z_{A3} contain identical elements which cooperate and function in the same way as the branches Z_{A1} and Z_{A3} in Figure 5. In the branch Z'_{A2} , the acoustical impedance is composed of the following elements:

M'_{A2} =inertance of the air in aperture or opening 17

M'_{A3} =inertance of the screen 37

r'_{A3} =acoustical resistance of the screen 37

M''_{A3} =inertance of the screen 39

r''_{A3} =acoustical resistance of the screen 39

M'''_{A3} =inertance of the screen 41

r'''_{A3} =acoustical resistance of the screen 41

M'_{A4} =inertance of the air load upon the screen being used and the opening 17

r'_{A4} =acoustical resistance of the air load upon the screen being used and the opening 17

The analysis and functioning of the branch Z'_{A2} in comparison with that of the branch Z_{A2} is identical except that the values of the inertance and acoustical resistance of the screen will change according to the particular screen selected for use.

Other changes will, no doubt, readily suggest themselves to those skilled in the art. We therefore desire that the above description and the form of our invention shown in the accompanying drawings shall be taken as illustrative and not as limiting.

We claim as our invention:

1. In a sound translating device, the combination of means providing an air gap and a mag-

netic field in said gap, a conductor mounted in said gap for vibration therein in response to sound wave energy, said conductor and gap constituting a conductor branch of said translating device which has a characteristic acoustic resistance, a pipe mounted behind said conductor in close proximity thereto and including means constituting a terminating acoustic resistance for said conductor, said conductor substantially closing the mouth of said pipe, said pipe having an opening therein behind said conductor and means disposed over said opening constituting an acoustic resistance behind said opening, said last named means comprising a screen formed of threads having such diameter and spacing that said screen has an acoustic resistance which is comparable to the air in said opening and acts to compensate for the acoustic resistance in said conductor branch whereby to lower the low frequency response of said translating device due to back waves.

2. A sound translating device according to claim 1 wherein said opening is of such dimension as to impart to said device a substantially unidirectional characteristic.

3. In a sound translating device, the combination of means providing an air gap and a magnetic field in said gap, a conductor mounted in said gap for vibration therein in response to sound wave energy, said conductor and gap constituting a conductor branch of said translating device which has a characteristic acoustic resistance, a pipe mounted behind said conductor in close proximity thereto and including means constituting a terminating acoustic resistance for said conductor, said conductor substantially closing the mouth of said pipe, said pipe having an opening therein behind said conductor, means providing for said opening a plurality of acoustic resistance elements, each of said acoustic resistance elements comprising a screen formed of threads having such diameter and spacing that the screen has an acoustic resistance which is comparable to the air in said opening and acts to compensate for the acoustic resistance in said conductor branch whereby to lower the low frequency response of said translating device due to back waves, the thread diameters and spacing of each of said screens being different whereby each screen has a different, fixed value of resistance than the other of said screens, and means for selectively placing any one of said elements over said opening.

4. A sound translating device according to claim 3 characterized in that the means for selectively placing any one of said acoustic resistance elements over said opening comprises a member movably mounted on said pipe over said opening, said movable member carrying said plurality of screens in spaced relation therealong whereby any preselected one of said screens may be brought into registration with said opening by moving said member along said pipe.
